UNITED STATES PATENT OFFICE.

MAX JOHN AHLGRIM, OF ROSE LAWN, INDIANA.

CALF-WEANER.

SPECIFICATION forming part of Letters Patent No. 291,660, dated January 8, 1884.

Application filed August 14, 1883. (Model.)

To all whom it may concern:

Be it known that I, MAX J. AHLGRIM, of Rose Lawn, in the county of Newton and State of Indiana, have invented a new and Improved 5 Calf-Weaner, of which the following is a full, clear, and exact description.

My invention consists of a half-muzzle of wire armed with pointed barbs, and arranged over the nose of the calf on pivots of a halter 10 at the cheeks, and balanced by a weighted arm, so that when the calf raises the nose to suck the points will be pressed against the cow's udder by the calf's nose, and when the calf holds the head in the natural standing position, 15 or lower, the said half-muzzle will swing clear of the nose, so as not to interfere with feeding or be a cause of annoyance to the calf, all as hereinafter fully described.

Reference is to be had to the accompanying 20 drawings, forming part of this specification, in which similar letters of reference indicate corresponding parts in all the figures.

Figure 1 is a perspective view of a calf's head in the natural standing position with my improved weaner attachment applied. Fig. 2 is 25 a side elevation of the same, the nose being lifted up as for sucking the cow; and Fig. 3 is a perspective view of the weaner detached from the calf's head.

At or about the junctions of the nose-strap 30 *a* and the throat-strap *b*, with the cheek-straps *c* of a common halter fitted to the calf's head, I arrange stud-points *d*, forming barbs, and also forming pivot-studs for a wire yoke, *e*, which 35 extends around the end of the nose with sufficient clearance at said end for swinging clear of the nose to support barbs *f*, and between the pivots *d* and the bow at the end of the nose I arrange a bow, *g*, in connection with the two 40 members of the yoke and extending over the nose from side to side of the yoke. This bow is connected with the bow of the front end of the yoke by two curved wires, *i*, for stays, the whole making a half-muzzle for the support of 45 said barbs *f*, and others, *j*, to prick the udder of the cow, and thus prevent the calf from sucking. The yoke *e* has another yoke, *k*, formed on it, and extending from the eyes *l* downward under the throat of the calf nearly

at a right angle and a sufficient length to balance the yoke *e* in a horizontal plane, or thereabout, by a weight, *m*, so that the nose of the calf will drop clear of the weaner, except when raised in the position for sucking. I also prefer to connect the pivots *l* of the yoke *e* 55 with a yoke, *n*, extending under the throat or lower jaw; but this may be used or not, as preferred.

This device will effectually accomplish the desired purpose without injury to the calf or 60 material inconvenience. The wires forming the half-muzzle may be varied to some extent in their arrangement, if desired.

I do not mean to limit myself to the use of wire in the construction of the above-described 65 weaner, but may prefer to use flat bar-iron, particularly for the yokes *e* and *k*, with holes punched for the eyes *l* for the pivots *d*. The bow *g* may also be of flat bar, and said bow and bow *e* may have eyes punched for the pivots *j* and *f*, formed on stays *i* of flat bar, to project through for being more substantially supported against being wrenched off against the fence, trees, and other objects; and if preferred the whole device, except the throat-yoke *n*, may be made in malleable iron. 75

It is to be noted that the studs *d* are formed on the throat-yoke *n* and pass through the halter and eyes *l* so as to be well supported.

In practice the throat-strap *b* of the halter 80 will have a buckle for adjusting it to the size of the calf to which the device is to be attached.

Having thus described my invention, I claim as new and desire to secure by Letters Patent— 85

1. The improved calf-weaner consisting of a half-muzzle, made of wire or other suitable material, armed with barbs and arranged over the nose on pivots *d* of a halter, located at the cheeks, and provided with a balance-weight, holding said muzzle above the nose, except when raised to suck, substantially as described. 90

2. The combination, in a calf-weaner, of the yoke *e*, nose-bow *g*, stays *i*, balance-yoke *k*, and weight *m*, with a halter having pivot-studs *d*, said yoke *e* and nose-bow *g* being provided with barbs, substantially as described. 95

3. The combination, in a calf-weaner, of the yoke *e*, nose-bow *g*, stays *i*, balance-yoke *k*, weight *m*, and the throat-yoke *n*, forming pivot-studs *d* and fastening to halter, said yoke *e* and bow *g* being provided with barbs, substantially as described.

4. In a calf-weaner, the combination, with the yokes *e k*, having eyes *l*, of the throat-yoke

n, having studs *d* passing through said eyes from the inside, as shown and described.

MAX JOHN AHLGRIM.
